ABSTRACT

A magnetic core having a plurality of lamination layers. Gaps are located in the lamination layers to reduce residual magnetic flux and are displaced from each other in adjacent lamination layers to form a stepped gap pattern across the magnetic core. A sheet of solid insulating material is disposed in the gaps formed by the lamination layers to maintain the length of the gaps.

FIG.2

FIG.2B

FIG.3

MAGNETIC CORE STRUCTURES FOR INSTRUMENT TRANSFORMERS

BACKGROUND OF THE INVENTION

1. Field of the Invention

This invention relates, in general, to electrical inductive apparatus and, more specifically, to magnetic cores for instrument transformers.

2. Description of the Prior Art

Instrument transformers are used to monitor voltages and currents existing in power transmission and distribution systems. Current-type instrument transformers, or current transformers, usually include a magnetic core structure having a winding disposed thereon. The core and winding assembly are suitably placed in the magnetic field created by the current to be measured. A change in the measured current produces a change in the surrounding flux, thus the voltage induced into the winding of the current transformer is changed.

Current transformers which are placed around electrical bushings generally have a closed magnetic core of circular shape. Prior art current transformers constructed in this manner have a substantially continuous magnetic core structure which does not contain any air gaps. Also, prior art cores used in current transformers contain no joint at all since it is practical to wind the winding around a closed core.

The performance of current transformers is critical when used in control systems which regulate or switch electrical power between circuits. In order for the performance to be adequate, the current indications provided by the current transformer must be sufficient to properly control the associated components.

Current transformers are used in connection with a variety of functions, including metering and relaying. The output from the current transformer must be sufficiently representative of the measured current to provide the proper metering or relaying action.

The current being measured may be interrupted at any point during the polarity cycle; therefore, the possibility of creating a residual flux in the magnetic core of the current transformer is great. When using conventional core materials and construction arrangements, the residual flux may be as high as 90 percent of the peak flux during normal operation.

Residual flux may present errors or incorrect control of the components and circuits connected to the current transformer. When the current being measured begins to flow after a period during which current did not flow, the flux provided by the flowing current is added vectorially to the residual flux. The result is an incorrect current transformer output. If the induced and residual fluxes are in phase, saturation of the magnetic core may occur.

The residual flux is reduced to a nominal value after several cycles of alternating flux have been induced into the core. This partly accounts for the feasibility of using current transformers susceptible to relatively high residual flux components with conventional meters and relays. With the advent of metering and relaying components which respond quickly, the instantaneous response of current transformers is becoming more important. Therefore, it is desirable, and it is an object of this invention, to provide a current transformer which exhibits relatively low residual flux components.

Several methods may be used to reduce the residual flux in current transformer cores. Selection of the magnetic material is important and magnetic steels are available which yield relatively low residual flux components. However, such materials are costly and their use is undesirable from an economic standpoint. Therefore, it is desirable, and it is an object of this invention, to provide a current transformer which exhibits relatively low residual flux components with the use of standard grade magnetic steel materials.

The theory on the use of air gaps in magnetic cores to reduce the residual flux components is known by those skilled in the art. A magnetization curve for a magnetic core illustrates the magnetic flux density "B" with respect to the magnetic field intensity "H". The maximum amount of residual flux is depicted graphically as the amount of flux density which exists when the field intensity is zero. This occurs where the magnetization curve crosses the ordinate corresponding to

15 zero field intensity. By introducing an air gap into the magnetic core, the magnetization curve is shifted and intercepts the zero field intensity ordinate at a lower point than the curve without an air gap.

Unfortunately, reducing residual flux by constructing 20 an air gap in the magnetic core increases the field intensity required to produce a given amount of flux density. To keep the magnetic characteristics of the magnetic core within usable limits, the effective air gap must be kept as small as possible while still providing 25 a significant reduction in the maximum residual flux.

Conventional air gap arrangements and construction 30 techniques exhibit certain characteristics which make the use of conventional air gaps in current transformer cores unsatisfactory. An air gap cut straight across the

35 magnetic core has the same gap surface area as the cross-sectional area of the magnetic core. To keep the flux density and the field density relationship within satisfactory limits in current transformer cores, the length of the gap must be extremely small. Non-magnetic material placed in the gap region to maintain 40 its length would be so thin that material now available would not be physically strong enough to resist the mechanical forces subjected upon the gap during the life of the current transformer. Therefore, it is desirable, 45 and it is an object of this invention, to provide a current transformer core wherein the effective gap is less than the actual gap, thereby allowing readily available materials to be inserted therein to maintain the gap length.

The length of an air gap which is cut straight across 50 a magnetic core is difficult to keep constant because of difficulty in bracing the core in the gap region. Under high flux conditions, such a gap tends to become wedge-shaped, thereby changing the effective gap distance and the characteristics of the magnetic core. A gap positioned straight across a magnetic core causes 55 a certain amount of losses due to unavoidable burrs on the ends of the lamination layers of the magnetic core which are produced during the cutting of the gap. In the straight-across gap, the burrs are aligned symmetrically about the longitudinal axis of the core; that is, across the flat face of the gap. Burrs from one lamination layer contact adjacent lamination layers and an eddy current path across the face of the gap may be established. Therefore, it is desirable, and it is an object 60 of this invention, to provide a current transformer core wherein a gap therein may be adequately braced to prevent distortion thereof and which may be constructed 65

to reduce eddy current losses occasioned by the alignment of burrs on the end of the core lamination layers.

SUMMARY OF THE INVENTION

There is disclosed herein a new and useful magnetic core structure for current-type instrument transformers. The core includes a plurality of lamination layers containing gaps between the ends thereof. Adjacent lamination layers are displaced in a predetermined pattern to provide a stepped gap pattern across the magnetic core. A solid insulating material is placed in the gaps to maintain the spacing or length thereof. By stepping the gaps, the gaps are positioned diagonally across the magnetic core. This increases the gap area and effectively allows the length of the gap to be increased to a practical value. Stepping the gaps also distributes the burred ends of the lamination layers, and thus reduces eddy currents at the face of the gap.

BRIEF DESCRIPTION OF THE DRAWING

Further advantages and uses of this invention will become more readily apparent when considered in view of the following detailed description and drawing, in which:

FIG. 1 is an elevational view of an electrical bushing assembly having a current transformer positioned thereon;

FIG. 2 is a view of a magnetic core constructed according to this invention;

FIGS. 2A and 2B are detail views of the gap region encircled in FIG. 2; and

FIG. 3 is a graph illustrating magnetization curves for magnetic cores constructed with and without gaps.

DESCRIPTION OF THE PREFERRED EMBODIMENTS

Throughout the following description, similar reference characters refer to similar members in all figures of the drawing.

Referring now to the drawing, and FIG. 1 in particular, there is shown an electrical bushing 10 with a bushing-type current transformer 12 disposed thereon. The bushing includes the expansion cap 14, the upper insulator 16, the lower insulator 18, and the conductor tube 20. The bushing 10 is attached to the enclosure 22 of the electrical apparatus on which the bushing is mounted, such as a power transformer.

The current transformer 12 is positioned around the lower insulator 18. The current transformer 12 includes a laminated magnetic core 24, a winding structure 26 disposed thereon, and solid insulation 28 disposed around the core and winding assembly. The leads 30 provide means for transferring an electrical output to associated metering or relaying apparatus.

The magnetic core 24 is constructed of layers of laminations which are disposed concentrically about each other. FIG. 2 is a view of the magnetic core 24 illustrating novel features of its construction. An inner lamination layer 32 contains a gap at location 34. An outer lamination layer 36 contains a gap at location 38. Intermediate lamination layers 40 are positioned between the inner lamination layer 32 and the outer lamination layer 36. Gaps in adjacent lamination layers are displaced to form a stepped gap pattern across the magnetic core 24. It is within the contemplation of this invention that the general shape of the magnetic core 24 may be other than circular, such as square or rectangu-

lar. Bands or straps 31 are positioned around the core to conveniently hold the gap region 33 together.

Portion 2A of FIG. 2 is shown in FIG. 2A which illustrates in detail the arrangement of the stepped gaps according to one embodiment of this invention. A spacer 42 is placed between the lamination layers as shown to maintain the length of the gaps. The spacer 42 is constructed of a solid insulating material such as cellulosic kraft paper, wholly aromatic polyamide paper, polyimide film, or any other suitable material. Gap 44 is created by the separation of the ends 46 and 48 of the lamination layer 50. The adjacent gap 52, which is formed by the adjacent lamination layer 54, is transversely displaced from the gap 44. The amount of gap displacement depends on the thickness of the spacer 42, the thickness of the lamination layers, and the distance adjacent lamination layers are stepped. It has been determined that a practical core may be constructed when the gap displacement is approximately six times the lamination thickness.

The thickness of steel lamination layers is generally about 0.011 inch to 0.102 inch. The thickness of the spacer may vary depending on the size and rating of the current transformer. Typical values range between 0.001 inch and 0.100 inch. The gap length may be changed conveniently by changing the thickness of the spacer 42, or by placing a plurality of spacers 42 in the gap region 33.

A transverse gap displacement in adjacent laminations equal to six times the thickness of a lamination layer provides a practical compromise between satisfactory core performance and convenient core construction. The relative position of the end 48 with respect to the end 56 depends on the manner in which the core is constructed, and they may be displaced from each other differently than shown in FIG. 2A without departing from the spirit of the invention.

Generally, the dimensions of the spacer 42 are sufficient to provide spacing material located throughout the longitudinal distance of the joint which is perpendicular to the plane of FIG. 2A. The thickness of the spacer 42 is an important factor in governing the shape of the spacer 42 in a complete core. A relatively thick spacer 42 would maintain a substantially straight shape when moderate pressures are applied by the bands 31. A relatively thin spacer 42 would conform to the stepped shape formed by the lamination layer ends.

FIG. 2B illustrates an embodiment of this invention wherein adjacent lamination layers overlap for a short distance. The spacer 42 is curved to conform somewhat to the lamination layer steps. With a thin flexible spacer 42, the spacer 42 may fill the gaps completely when the stepping distance is reduced to the thickness of the spacer 42.

FIG. 3 illustrates the upper portion of magnetization, or B-H, curves for magnetic cores. Curve 60 is representative of a magnetic core without a gap. When the field intensity decreases to zero, and remains at zero, the residual flux B_{R1} in the ungapped core may be as high as 90 percent of the peak flux.

Curve 62 is representative of a magnetic core containing a gap. The effect of a gap is to tilt the B-H curve of the core. This reduces the residual flux B_{R2} in the magnetic core. From curve 62, it can be seen that when the field intensity decreases to zero, the residual flux B_{R2} is much lower than that provided by the ungapped

core represented by curve 60. A suitable and workable value for B_{R2} is 10 percent of the peak flux density.

The novel magnetic core structure taught by this invention increases the overall core gap area, thus allowing an increase in gap length or spacing without changing the effective gap length compared to a gap cut straight across the core. This permits satisfactory placement of standard materials in the gap region to maintain the length of the gap. Burrs produced during the cutting of the lamination layers are displaced from the burrs of adjacent lamination layers, thus eddy currents due to lamination burrs are reduced. The solid insulating material contained within the gap allows the core to be clamped and banded tightly together while still maintaining the desired gap length.

Since numerous changes may be made in the above-described apparatus and different embodiments of the invention may be made without departing from the spirit thereof, it is intended that all of the matter contained in the foregoing description, or shown in the accompanying drawings, shall be interpreted as illustrative rather than limiting.

We claim as our invention:

1. A magnetic core for electrical inductive apparatus, comprising an inner lamination layer having a gap therein, an outer lamination layer having a gap therein, said outer lamination layer being concentrically located around said inner lamination layer, intermediate

lamination layers concentrically located between said inner and outer lamination layers with each intermediate lamination layer having a gap therein, the gaps in adjacent lamination layers being transversely displaced from each other to provide a stepped gap pattern which progresses radially across said magnetic core, and a sheet of solid insulating material disposed in said gaps to maintain the length of said gaps.

2. The magnetic core of claim 1 wherein the solid insulating material comprises a sheet of cellulosic paper.

3. The magnetic core of claim 1 wherein the solid insulating material comprises a sheet of wholly aromatic polyamide paper.

4. The magnetic core of claim 1 wherein the solid insulating material comprises polyimide film.

5. A magnetic core for a current-type instrument transformer, comprising a plurality of concentrically located cylindrical lamination layers, each of said lamination layers containing a gap, the location of gaps in adjacent lamination layers being transversely displaced from each other to provide a stepped gap pattern which progresses radially across said magnetic core, a sheet of solid insulating material disposed in said gaps to maintain the length of said gaps, and means for tightly pressing the ends of said lamination layers against said sheet of solid insulating material.
